UNITED STATES PATENT OFFICE.

JAMES A. GARLAND, JR., OF HAMILTON, MASSACHUSETTS.

INTERMEDIATE-LINE-SPACING DEVICE FOR TYPE-WRITING MACHINES.

SPECIFICATION forming part of Letters Patent No. 716,215, dated December 16, 1902.

Application filed March 7, 1901. Serial No. 50,183. (No model.)

To all whom it may concern:

Be it known that I, JAMES A. GARLAND, Jr., a citizen of the United States, residing at Hamilton, in the county of Essex and State of Massachusetts, have invented a new and useful Improvement in Intermediate-Line-Spacing Devices for Type-Writing Machines, of which the following is a specification.

The object of my invention is to provide an intermediate-line-spacing device for type-writing machines of the class employing a paper-roll or paper-cylinder, of which the Remington machine is a well-known example.

It is often desired to print letters or figures at some intermediate point between two normal lines of printing—as, for example, in writing exponents. To accomplish this without the aid of an intermediate-line-spacing device it is necessary for the operator to turn the paper-cylinder by hand the desired distance from the normal line, hold the cylinder while he prints the desired letters or figures, and then turn the paper-cylinder back to its original position for continuing the printing upon the normal line, or to slip the paper upon the paper-cylinder, print the intermediate-spaced characters, and then slip it back. Such manual adjustment necessarily causes much loss of time, and, furthermore, the distance of the points at which the intermediate-spaced characters are to be placed from the normal line can only be kept approximately constant by the exercise of the greatest care and attention, and consequently the work usually presents a more or less uneven and irregular appearance.

My intermediate-line-spacing device provides a means whereby the paper-cylinder may be turned or rotated a positive and predetermined distance independently of the line-spacing mechanism of the machine and will be automatically returned to its normal or original position for continuing the normal line. It requires no careful manipulation on the part of the operator, as does the turning of the cylinder or slipping of the paper by hand, and consequently makes greater speed possible in writing, and it renders the intermediate lines uniform and fixed at a predetermined distance from the normal line, which distance I have made provision to regulate, as desired.

In the accompanying drawings I show an embodiment of my invention applied to a No. 6 Remington type-writing machine. Only 55 those portions of the machine with which my invention is immediately concerned are shown in the drawings, as the machine as a whole is too well-known to require illustration or detailed description. It is, however, obvious 60 that my invention is adapted to be applied to any type-writing machine which employs a paper-cylinder adapted for spacing the lines.

In the drawings, Figure 1 is a plan view of one end of the paper-carriage and paper-cylinder and of my intermediate-line-spacing device attached thereto. Fig. 2 is a sectional view of the paper-carriage, taken through the line X X' of Fig. 1, showing in elevation my intermediate-line-spacing device in its normal 70 or inoperative position and the end of the paper-cylinder. Fig. 3 shows the same view of the parts as Fig. 2, except that the line-spacing device is shown in its operative position. Fig. 4 shows in plan view the platen 75 and its carriage, with the usual line-spacing mechanism at one end and the intermediate-line-spacing mechanism at the other.

The same parts are indicated by the same letters of reference in all the figures. 80

A represents the frame of the paper-carriage, and B the paper-roll or paper-cylinder. Concentric with the paper-cylinder B and mounted on the axis C of the paper-cylinder and securely keyed thereto or to the cylinder 85 is the cog-wheel or spur-wheel D. In the plane of the spur-wheel D is the movable arm E, which may be pivoted at the rod a, which usually supports the index adjacent to the paper-roll or at any convenient point. This 90 arm E is curved downward, so as to pass under the spur-wheel D, as is shown in Figs. 2 and 3. It is provided at its outer end with the lever or key E'. In its normal or inoperative position the arm E bears against the bottom 95 of the paper-carriage frame A, and the key E' may be used as the handle by which the paper-carriage is elevated for inspecting the writing. Integral with the arm E and in close proximity to and slightly above the center of 100 the spur-wheel D is the clutch F, adapted to engage with the cogs of the spur-wheel. The tension-spring S, attached to the frame A of the paper-carriage and to the arm E, normally

holds the clutch F out of engagement with the spur-wheel D. Consequently when my intermediate-line-spacing device is not in use it in no way interferes with the usual line-spacing mechanism of the machine. The arm E is provided with the finger or stop G, which coming into contact with the frame A of the paper-carriage limits the downward movement of the arm E. The length of such downward movement may be governed by using the set-screw H in the stop G. The number of cogs on the spur-wheel D corresponds to the number of cogs on the spur-wheel at the opposite end of the paper-cylinder, which forms a part of the ordinary line-spacing mechanism of the machine, so that in any position which the paper-cylinder may take under the control of the line-spacing mechanism of the machine a cog of the spur-wheel D will be brought into the proper relative position to the clutch F.

The operation of my device is as follows: The operator, desiring to print upon a line intermediate between the normal lines of print, depresses the arm E by means of the key or lever E', overcoming the tension of spring S, until the movement is arrested by the stop G or the set-screw H, when the latter is used. The initial movement of the arm E brings the clutch into engagement with the spur-wheel D, and the continued movement rotates the spur-wheel and the paper-cylinder the distance desired for the intermediate line-spacing. Upon releasing the key E' the spring S at once returns the arm E to its normal position against the under side of the frame A, and the clutch F, bearing upon the cog of the spur-wheel D next above it, returns the paper-cylinder to its original position and withdraws from engagement with the spur-wheel, leaving the paper-cylinder free to rotate under the control of the ordinary line-spacing mechanism of the machine.

The ordinary line-spacing device is indicated generally at N, Fig. 4, wherein n' is the operating-handle, and n^2 the clutch mechanism.

I do not intend to limit myself to the specific form of clutch described above, as it is obvious that a friction-clutch or other form of clutch adapted to engage the paper-cylinder by an initial movement and to rotate the same independently of the line-spacing mechanism of the machine is within my invention.

55 What I claim, and desire to secure by Letters Patent, is—

1. An intermediate-line-spacing device for type-writing machines, comprising a clutch normally out of engagement with the paper-cylinder, means for engaging the clutch with the paper-cylinder and for rotating the same independently of the line-spacing mechanism of the machine, and means for automatically returning the paper-cylinder to its original position under the influence of the clutch.

60 2. An intermediate-line-spacing device for type-writing machines, comprising a spur-

wheel concentric with and secured to the paper-cylinder and a clutch normally out of engagement with said spur-wheel and adapted to be moved into engagement with said spur-wheel and to rotate the paper-cylinder a predetermined distance independently of the line-spacing mechanism of the machine and means for automatically returning the paper-cylinder to its initial position under the influence of the clutch. 75

3. An intermediate-line-spacing device for type-writing machines, comprising a spur-wheel concentric with and secured to the paper-cylinder, and a clutch normally out of engagement with said spur-wheel and adapted to be moved into engagement with said spur-wheel and to rotate the paper-cylinder a predetermined distance independently of the line-spacing mechanism of the machine and adjustable means for limiting in scope the movement of the cylinder under the influence of the clutch to a distance less than a normal line-space, and means for automatically returning the paper-cylinder to its original position. 90

4. An intermediate-line-spacing device for type-writing machines comprising a spur-wheel concentric with and secured to the cylinder, and a clutch pivoted eccentrically with said spur-wheel normally out of engagement with said spur-wheel and adapted to be moved into engagement with said spur-wheel and to rotate the paper-cylinder a predetermined distance independently of the line-spacing mechanism of the machine, and means for automatically returning the paper-cylinder to its initial position under the influence of the clutch. 95

5. An intermediate-line-spacing device for type-writing machines comprising a spur-wheel concentric with and secured to the paper-cylinder, and a clutch pivoted eccentrically with said spur-wheel normally out of engagement with said spur-wheel and adapted to be moved into engagement with said spur-wheel and to rotate the paper-cylinder a predetermined distance independently of the line-spacing mechanism of the machine and adjustable means for limiting in scope the movement of the cylinder under the influence of the clutch to a distance less than a normal line-space and means for automatically returning the paper-cylinder to its original position. 110

6. An intermediate-line-spacing device for type-writing machines, comprising a spur-wheel concentric with and secured to the paper-cylinder, and a clutch resistingly held in its inoperative position out of engagement with said spur-wheel by means of a spring, and adapted to be moved into engagement with the spur-wheel and to rotate the paper-cylinder a predetermined distance independently of the line-spacing mechanism of the machine and automatically to return the paper-cylinder to its initial position. 115

7. An intermediate-line-spacing device for

type-writing machines comprising a spur-wheel concentric with and secured to the paper-cylinder, a clutch borne by an arm pivoted eccentrically with said spur-wheel, and 5 resistingly held in inoperative position out of engagement with said spur-wheel by means of a spring and adapted to be moved into engagement with said spur-wheel and to rotate the paper-cylinder independently of the line-spacing mechanism of the machine and to automatically return the cylinder to its initial position, and an adjustable stop to limit the movement of the clutch.

8. An intermediate-line-spacing device for 15 type-writing machines comprising a clutch normally out of engagement with the paper-

cylinder, adapted to rotate the latter in the direction opposite to the normal rotation for spacing the lines, means for engaging the clutch with the paper-cylinder and for rotating the cylinder in the aforesaid direction independently of the line-spacing mechanism of the machine and means for automatically returning the paper-cylinder to its original position under the influence of the clutch. 20 25

Signed by me, at Boston, Massachusetts, this 4th day of March, 1901.

JAMES A. GARLAND, JR.
